(57) **CLAIM**

The ornamental design for a battery pack, as shown and described.

DESCRIPTION

FIG. 1 is a front perspective view of a first construction of a battery pack.

FIG. 2 is a front view of the battery pack of FIG. 1.

FIG. 3 is a rear view of the battery pack of FIG. 1.

FIG. 4 is a left side view of the battery pack of FIG. 1.

FIG. 5 is a right side view of the battery pack of FIG. 1.

FIG. 6 is a top view of the battery pack of FIG. 1; and,

FIG. 7 is a bottom view of the battery pack of FIG. 1.

The ornamental design which is claimed is shown in solid lines in the drawings. The portions of the design shown in broken lines are included for the purpose of illustrating environment and form no part of the claimed design.
